Atty's.

UNITED STATES PATENT OFFICE.

ALEXANDER G. McGREGOR, OF WARREN, ARIZONA.

AUTOMOBILE-HOOD.

1,356,541.

Specification of Letters Patent. Patented Oct. 26, 1920.

Application filed October 21, 1918. Serial No. 258,980.

To all whom it may concern:

Be it known that I, ALEXANDER G. McGREGOR, a citizen of the United States, residing at Warren, in the county of Cochise and 5 State of Arizona, have invented or discovered certain new and useful Improvements in Automobile-Hoods, of which the following is a specification, reference being had therein to the accompanying drawings.

10 This invention relates to covers or hoods for enveloping the folded tops of automobiles or other vehicles and serving as protectors to exclude dust or water, and the invention has for its object to provide a hood or cover, of the class referred to, which may be conveniently placed and held in operative position, and may be readily removed when desired, all as will hereinafter more fully appear.

15 The present invention relates to certain improvements on the invention covered by my U. S. Patent No. 1,215,684, granted February 13, 1917.

In the accompanying drawings Figures 1 20 and 2 are perspective views of two slightly different forms of covers or hoods embodying the present invention. Figs. 3, 4 and 5 are enlarged detail sections taken on lines 3—3, 4—4 and 5—5, respectively, of Fig. 1. 25 Fig. 6 is a detail perspective view illustrating the forward part of the vent or opening in the top piece or upper side of the hood or cover, showing the flaps of the said vent or opening in opened positions. Fig. 7 is a detail section on line 7—7 of Fig. 2. Fig. 8 is a detail perspective view illustrating a modification of the invention, and Fig. 9 is an enlarged detail sectional view illustrating a preferred form of securing device for the 30 ends of the continuous tension strap.

Referring to the drawings, 1, 2, 3 and 4 denote the bottom, sides, back and top portions of the cover or hood, these portions being of usual flexible and preferably water- 45 proof material and properly secured together so as to be permanently associated and thus form a cover or hood which is practically all in one piece affording a front opening which will enable the cover or hood to be drawn 50 over the folded top of an automobile or other vehicle. The top portion 4 of the cover or hood is provided with an opening or vent afforded by separated edges which may be made in the form of overlapping 55 flaps 5 and 6. These flaps are preferably stiffened by thin metal bars 7 and 8 which

will be inclosed in pockets or receptacles preferably formed by folding the flexible material of the top portions 4 of the hood or cover upon themselves and securing these 60 folded-over portions together by lines of stitching 4^a. The bars 7 and 8 are preferably connected together near their rear ends by a loop or strap 9 of metal, leather or other suitable material, said strap passing 65 through slots or openings formed in said bars as shown in Fig. 3. This strap 9 serves as a hinge on which the said bars may swing when being opened out and closed together and also serves as a stay to prevent the material of the top portions 4 from being torn in opening the vent when the hood or cover is to be placed over the folded vehicle top.

The cover or hood is provided at its front portion with a continuous, flexible, tension 75 strap 10 which will be suitably held in place as by being located in pockets formed by folding the front edges of the material constituting the body of the cover or hood at the top and bottom of the hood back upon themselves, and securing these folded-over portions together by lines of stitching, as 4^b, Fig. 4. Pockets for the straps 10 may be formed near the front edges of the side portions 2 of the hood by folding in the front 80 edges of these side portions upon themselves, as shown in Fig. 5, and connecting these folded-in portions by lines of stitching as 2^a. The continuous tension strap 10 may be in one or more pieces, and said strap is pro- 85 vided with means whereby the ends thereof are suitably connected together, as by a buckle 21 secured to one end of said strap and coöperating with the opposite perforated end 22 of said strap; or the said strap 10 90 may be made in several sections connected together by buckles 15 and 16 as shown in Fig. 1, or by buckles 17 and 18, as shown in Fig. 2. These buckle connections will enable the said strap to be adjusted intermediate its ends for the purpose of giving it a suitable adjustment with reference to the different parts of the cover or hood. When the ends of the said strap are secured 100 together and the strap is made taut the front part of the cover or hood will be closed tightly around the folded vehicle top, so as to compress said folded top as also to tightly hold the front edge of the cover or hood against the same.

The tension or holding strap 10 will preferably be attached to the stiffening bars 7

and 8, near the forward ends of said bars by rivets 11 and 12, and the said strap will also preferably be attached to the top portions 4 of the cover or hood by rivets 19 and 20.

5 To hold the cover or hood in place over a folded vehicle top said cover or hood may be provided near its sides at its front portion with straps 23 and 24 which are adapted to engage some suitable stationary parts, as 10 shown in Fig. 1.

Instead of providing the hood with holding straps, as 23 and 24, just referred to, said hood or cover may be provided with bow covers 25 and 26, as shown in Fig. 2, 15 these covers each consisting of two separable parts or flaps adapted to be removably secured together along their edges, as by being provided with snap fasteners 27 or the like. These bow covers will preferably be 20 provided at their front portions with attaching straps 28 to be secured to any suitable stationary parts on the vehicle.

The strap 10 instead of being held in pockets at the sides 2 of the cover or hood, 25 as above described, may be retained in place by suitable keepers, as 13, 14; consisting of loops attached to the material of the sides 2 in any suitable manner as by lines of stitching 2^b, as will be understood from 30 Fig. 7.

In the construction shown in Fig. 8 the straps 23 and 24, shown in Fig. 1 and the bow covers shown in Fig. 2 are omitted, and in this modified form the tension strap 10 35 will be relied upon to retain the cover or hood in place on a folded vehicle top.

Instead of securing the ends of the tension strap 10 together by the means shown in Fig. 6 the means shown in Fig. 9 may be 40 employed. In this securing construction, which is considered preferable, a metal loop or ring 29 is suitably connected with one end of said strap at one of the separated edges of the vent in the top portion 4 of the 45 hood, and a perforated strap 30, adapted to be drawn through said loop or ring, is connected with the other end of said strap at the other separated edge of said vent, said strap 30 being secured by a buckle 21^a also 50 connected with said strap.

By providing what is practically a single piece cover or hood with a vent at the upper side or top portion thereof the said vent may be more conveniently closed or opened 55 in securing the cover or hood in place over a folded vehicle top or in removing it therefrom, than would be the case if the said vent were formed at the lower side or bottom of the said cover or hood, as will be 60 understood. Also by providing the stiffened separated edges constituting the vent or opening in the upper side or top portion of the cover or hood with a loop or stay, as 9, any danger of tearing the material of the 65 said cover or hood in opening the vent will

be entirely avoided. Also by providing a tension strap which passes continuously around the front portion of the cover or hood, and which strap may be secured together at its ends to draw the front portion 70 of the cover or hood suitably tight over the folded vehicle top, convenience and efficiency will be secured, and as said strap is secured in place at the front portion of the cover or hood it cannot be accidentally displaced or 75 lost.

Having thus described my invention I claim and desire to secure by Letters Patent:

1. A cover or hood for folded vehicle tops 80 consisting of bottom, side, back and top portions permanently associated so that the body of said cover or hood is practically in one piece, said cover or hood having at its top portion a vent afforded by separated 85 edges which may be closed together or opened out, when desired, and said cover or hood being provided with strap-receiving pockets at its front portion, combined with a continuous tension or holding strap inserted in said pockets and being thus attached to and adapted to pass around the front part of said cover or hood and a folded vehicle top, said strap being provided, at said vent, with means for remov- 90 ably securing its ends together.

2. A cover or hood for folded vehicle tops 95 consisting of bottom, side, back and top portions permanently associated so that the body of said cover or hood is practically in one piece, said cover or hood having at its top portion a vent afforded by separated 100 edges which may be closed together or opened out, when desired, and said cover or hood being provided with strap-receiving pockets at its front portion, combined with a continuous tension or holding strap inserted in said pockets and being thus attached to and adapted to pass around the front part of said cover or hood and a 105 folded vehicle top, said strap being formed in several adjustable sections and being provided, at said vent, with means for remov- 110 ably securing its ends together.

3. A cover or hood for folded vehicle tops 115 consisting of bottom, side, back and top portions permanently associated so that the body of said cover or hood is practically in one piece, said cover or hood having at its top portion a single vent afforded by sep- 120 arated edges which may be closed together or opened out when desired, said separated edges being provided with stiffening bars, combined with a metal stay loop passing through the rear ends of said bars, and thus 125 affording a strong hinged connection for said rear ends.

In testimony whereof I affix my signature.

ALEXANDER G. McGREGOR.
